CLAIM

The ornamental design for a combined garbage and recycling dual chamber container, as shown and described.

DESCRIPTION

FIG. 1 is a left front perspective of a combined garbage and recycling dual chamber container, showing my new design; FIG. 2 is an elevational view of the left hand side, thereof, the elevational view of the right hand side being a mirror image, thereof;

FIG. 3 is a front elevational view, thereof;

FIG. 4 is a rear elevational view, thereof;

FIG. 5 is a top plan view, thereof;

FIG. 6 is a bottom plan view, thereof; and,

FIG. 7 is a perspective view as in FIG. 1, but showing the chamber covers pivoted upwardly into an alternate position.
